UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

SIDE-BEARING SUPPORT FOR TRUCK BOLSTERS.

Application filed September 22, 1927. Serial No. 221,191.

This invention pertains to bolster reinforcements, and more particularly to braces for bolster or other side bearings.

The present A. R. A. specifications for 5 bolster design requirements, stipulate maximum stresses with a vertical load acting a certain distance each side of the center of said bolster; also anywhere from the center of the spring support to a fixed point from 10 the center of the bolster. These requirements were made with a view to insure proper strength of the bolster at the side bearings where the equivalent of the entire load of one truck may be concentrated due to the side 15 roll of the car and the impact consequent to side bearing clearance. It is therefore necessary to reinforce the top member of the bolster at the side bearings where some sort of support is necessary for this comparatively 20 thin section, this being especially true where the said bearings are of the roller type using a single roller, in which case the load is concentrated on an extremely limited area. Various methods of reinforcement for the top 25 member directly below the point of the side bearing have been devised but these generally take the form of a vertical or double web extending vertically between the top and bottom members, which forms have been found 30 to be not entirely satisfactory.

It is therefore an object of this invention to provide integral bolster reinforcing means disposed to insure proper strength of the bolster at the side bearings.

Another object is to provide side bearing reinforcement which is economical to manufacture and fulfills all requirements of service and manufacture.

A further object is to provide a reinforcement for side bearings so disposed as to properly distribute loads otherwise concentrated on an extremely limited area of the bearing.

With these and various other objects in view, the invention consists of certain novel 45 features of construction and operation as will be more fully described and particularly pointed out in the specification, drawings and claims appended hereto.

In the drawings, wherein like reference 50 characters are used to designate like parts—

Figure 1 is a side elevation of a bolster embodying the invention;

Figure 2 is a top plan view of the bolster shown in Figure 1;

Figure 3 is a sectional elevation taken substantially in the plane as indicated by the line 3—3 of Figure 1, showing a form of reinforcing braces for the side bearing; 55

Figure 4 is a sectional elevation showing a modified form of the bracing shown in Figure 3; and 60

Figure 5 is a sectional elevation of another modification of the bracing shown in Figure 3.

The bolster 10 may take the form generally of a trussed box girder and includes column guides 11 with adjacent top and bottom reinforced lightening holes 12, side bearings 13 adjacent spring supports 14, reinforced top and bottom web lightening holes 15 and a center bearing 16. The bolster may be further formed sloping upwardly and somewhat contracted toward the center toward the raised center bearing 16, and it may be desired to further form said bolster having the deepest 75 section adjacent the center and reinforced transversely of the bolster by braces 17 which are in the nature of column or center sill supports.

Referring now more particularly to Figure 80 3, the top and bottom webs 18 and 19 of the bolster adjacent the side bearing 13 may be connected by diagonally disposed brace members 20 of substantially inverted V-type. The corners of these braces are filleted so as also 85 to form a connection as at 21 to the side members 22 of the bolsters in order to better distribute the load concentrated on the side bearing. To further strengthen the diagonal members 20, which preferably extend in the 90 direction of the length of the bolster, brackets 23 may be disposed between said webs, forming a connection and brace between them. In some instances, in order to better adapt the bolster to bolt hole arrangements, instead of 95 providing the center brackets 23, side brackets 24 (Figure 4) may be provided forming a connection between the side webs 22 and the diagonal braces 20. The diagonal braces may be further reinforced by providing side 100

brackets 25 similar to the brackets 24 disposed between the diagonal braces 20 and the side webs 22 (Figure 5) and by forming a connection between the diagonal braces 5 by means of a bracket 26, similar to the bracket 23, disposing the brackets 26 and 25 so that they may be either in a line or in staggered relation with respect to each other.

It will therefore be seen that there has been 10 provided a bolster construction which conforms to the A. R. A. specifications for bolster design and includes reinforcement for a side bearing providing bracing means disposed in the direction of the stresses applied to the bearing and also providing outer bracing means disposed at an angle to the direction of the application of the stresses for reinforcing the first named bracing means, the side bearing and the bolster.

15 20 It is of course to be understood that I do not wish to be limited by the exact embodiments of the invention shown as other and various modifications will of course occur to those skilled in the art.

25 I claim:

1. In a bolster, the combination of side bearings, spring supports, and diagonal bracing means for said side bearings adjacent said spring supports.
2. In a bolster, the combination of side bearings, spring supports, and V-shaped braces disposed in the direction of the length of said bolster for said side bearings adjacent said spring supports.
3. In a bolster, the combination of side bearings, spring supports, V-shaped braces disposed in the direction of the length of said bolster for said side bearings adjacent said spring supports, and bracing means for said braces disposed transversely of said bolster.
4. In a bolster, the combination of side bearings, spring supports, V-shaped braces disposed in the direction of the length of said bolster for said side bearings adjacent said spring supports, and bracing means for said braces disposed transversely of said bolster and connecting parts of said bolster and said braces.
5. A bolster comprising an upper surface having a portion for receiving a side bearing, diagonally disposed bracing means for said upper surface reinforcing said portions and extending to and transmitting the load to other portions of said bolster.
6. A bolster of substantially rectangular truss construction having a portion throughout its length adapted to receive or serve as a side bearing, a diagonal brace extending from an intermediate portion of the underside of the top web to the lower portion of one of the side walls located to reinforce said portion.
7. A bolster of substantially rectangular truss construction having a portion throughout its length adapted to receive or serve as

a side bearing, a pair of oppositely extending diagonal braces extending from an intermediate portion of the underside of the top web to the lower portions of the side walls located to reinforce said portion.

70 75 8. A bolster of substantially rectangular truss construction having a portion throughout its length adapted to receive or serve as a side bearing, a pair of oppositely extending diagonal braces extending from an intermediate portion of the underside of the top web to the lower portions of the side walls located to reinforce said portion, and transverse webs extending between said braces.

80 85 9. A bolster of substantially rectangular truss construction having a portion throughout its length adapted to receive or serve as a side bearing, a pair of oppositely extending diagonal braces extending from an intermediate portion of the underside of the top web to the lower portions of the side walls located to reinforce said portions, and transverse webs extending between said braces and side walls of said bolster.

90 95 10. A bolster having a top surface and side walls, a portion for receiving side bearing stresses on said top surface, bracing means for said portion comprising an inverted V extending from the underside of said top surface to said side walls.

100 105 11. A bolster having a top surface and side walls, a portion for receiving side bearing stresses on said top surface, bracing means for said portion comprising an inverted V extending from the underside of said top surface to said side walls, and other bracing means extending between said side walls and first named bracing means.

110 115 12. A bolster having a top surface and side walls, a portion for receiving side bearing stresses on said top surface, bracing means for said portion comprising an inverted V extending from the underside of said top surface to said side walls, and other bracing means extending between the diverging portions of said V bracing means.

120 125 13. A bolster having a top surface and side walls, a portion for receiving side bearing stresses on said top surface, bracing means for said portion comprising an inverted V extending from the underside of said top surface to said side walls, and other bracing means extending between the diverging portions of said V bracing means and said walls.

130 135 14. A bolster having a top surface, bottom and side walls, a portion for receiving side bearing stresses on said top surface, bracing means for said portion comprising an inverted V extending from the under side of said top surface to the jointures between the bottom and side walls.

130 135 15. A bolster having a top surface, bottom and side walls, a portion for receiving side bearing stresses on said top surface, bracing

means for said portion comprising an inverted V extending from the under side of said top surface to the jointures between the bottom and side walls, and other braces between said side walls and the diverging portions of said inverted V bracing means.

5 16. A bolster having a top surface, bottom and side walls, a portion for receiving side bearing stresses on said top surface, bracing

means for said portion comprising an inverted V extending from the under side of said top surface to the jointures between the bottom and side walls, and other bracing means extending between the diverging portions of said inverted V bracing means.

10 15
Signed at Chicago, Illinois, this 17th day of September, 1927.

JOHN A. LAMONT.
